UNITED STATES PATENT OFFICE.

ELLIS J. G. PHILLIPS, OF AURORA, ILLINOIS, ASSIGNOR TO RICHARDS-WILCOX MANUFACTURING COMPANY, OF AURORA, ILLINOIS, A CORPORATION OF ILLINOIS.

DOOR-LOCKING DEVICE.

1,317,820.

Specification of Letters Patent.

Patented Oct. 7, 1919.

Application filed October 3, 1918. Serial No. 256,694.

To all whom it may concern:

Be it known that I, ELLIS J. G. PHILLIPS, a citizen of the United States, and a resident of Aurora, in the county of Kane and State 5 of Illinois, have invented certain new and useful Improvements in Door-Locking Devices, of which the following is a specification; reference being had to the accompanying drawings.

10 This invention relates to that type of locking mechanism for doors comprising two bolts that are simultaneously projected in opposite directions by the turning of a handle member with which said bolts are connected, such projection of the bolts causing a locking of the door at opposite points thereon. The invention has for its objects to provide a sectional construction of bolt that will enable its being promptly and 15 readily applied to a door regardless of the height thereof; to provide a construction of operating means for the locking bolts that can be applied without change to doors of varying thicknesses and can be locked when 20 so applied to prevent the withdrawal of the bolts after they have been projected into door-secur ing position; and to improve generally devices of this general type. I attain these objects by the means shown in the 25 drawings and hereinafter described. That which I believe to be new will be set forth in the claims.

In the drawings,—

Figure 1 is a perspective view of a pair 30 of swinging doors to one of which is applied my improvements;

Fig. 1^a is a perspective view of the upper one of the adjustable plate members of the sectional locking bolt, the view showing the 40 inner face of such member;

Fig. 2 is a detail being an enlarged view partly in vertical section and partly in elevation of that portion of the mechanism shown in the upper part of Fig. 1;

Fig. 3 is a detail, being a front elevation of the means for projecting and withdrawing the locking bolts—a portion of the casting in which such means are housed being broken away and the operating handle and 45 the nut that secures the same in place on the shaft being removed;

Fig. 4 is a detail showing the position of the bolt-projecting means when the bolts have been moved into locking position;

Fig. 5 is a vertical central section through the parts shown in Fig. 3, but with some parts in elevation;

Fig. 6 is a perspective view of the bolt-operating handle upon the outside of the door and the member that is connected to such handle and passes through the lock on the door;

Fig. 7 is a perspective view of an angular sleeve carried by the member that the door-handle shown in Fig. 6 has attached to it;

Fig. 8 is a view partly in front elevation and partly in vertical section of the means for locking the door-bolts against withdrawal after they have been projected into door-locking position, a portion of the front 70 plate of the lock-casing being broken away; and

Figs. 9 and 10 are sections taken at the lines 9—9 and 10—10 respectively of Fig. 2.

Referring to the several figures of the drawings,—A and B indicate two ordinary hinged doors that together are adapted to close an opening in the wall of a building. A portion of the doorway frame is shown, the upright member being indicated by C and the upper cross-bar by D. To one of these doors—in the illustration the one marked A—is attached my improved mechanism for locking the doors in closed position. Referring to such mechanism,—15 indicates a shaft angular in cross-section and which is connected with the key operated locking mechanism that is set in the front face of the door as shown. Such shaft projects from the inner face of the door and 80 through an opening in a face plate 16 secured to the door. Upon such projecting end of the shaft there are mounted, in the construction shown, two plates or disks 17 secured together but held at a distance from 85 each other by means of two oppositely located rivets 18—19. To the rivet 19 is pivotally attached one end of an arm 20 and to the rivet 18 is pivotally attached one end 90 of a similar arm 21. When the shaft 15 is 95 rocked, as hereinafter described, it will, of course, cause a turning of the plates or disks that are mounted thereon and thus cause the said arms 20—21 to move from or toward each other accordingly as the locking bolts carried by them are to be moved into or withdrawn from door securing position.

In Fig. 3 the arms are shown as re-

tracted, while in Fig. 4 they are shown as extended, and it will be noted that the pivots 18 and 19 pass slightly beyond the axis of the bolt so as to insure the parts being retained in position. The inner ends of these arms 20—21 are so shaped that when the arms are in their retracted position shown in Fig. 3 practically the entire space between the plates or disks will be occupied 10 by such inner portions of the arms.

To each of the arms 20—21 is secured a locking bolt adapted to engage in sockets formed respectively in the upper frame member of the doorway and in the floor. 15 Such securing sockets are shown in Fig. 1, the socket plate in the upper part of the framework being indicated by *a* and that in the floor by *b*. The locking bolt member that is secured to the arm 20 is in the construction shown formed of a number of sections. The section immediately connected with the arm 20 is indicated by 22. Its inner end is reduced in diameter as clearly shown in Fig. 5, and such reduced end carries 25 a stud 23 securely affixed thereto, which stud projects through an opening in the outer end of the arm 20, thus pivotally securing the parts 20 and 22 together. 24 indicates another bolt section similar to 22 and connected to the section 22 by a nut 25 screwed upon the adjacent ends of such sections 22 and 24, and 26 indicates still another section secured in like manner to the adjacent end of the section 24 by a nut 27. 30 The outermost section of the upper bolt is indicated generally by 28 and it comprises a sheet metal part and a cylindrical plug riveted or otherwise firmly secured thereto. The sheet metal part is formed of a flat 35 strip having an outwardly-bowed semi-cylindrical central channel 29 adapted to overlie the upper bolt section 26, the portions of the sheet at the sides of such channel 29 extending laterally therefrom in the same 40 plane and forming what may be termed wings and which are designated as 29^a. At regular intervals openings 30 are formed at opposite sides of the semi-cylindrical raised portion 29 so that by passing a pin 31 through any pair of such openings and through an opening in the upper member 26 of the sectional bolt the plate member 28 and the member 26 may be secured together in any adjusted position. The lower 45 end of the plate member 28 is shaped, as best shown in Fig. 1^a, to provide an extension of the channel 28, such extension being indicated by 32. The edges of this curved extension project a little beyond the face 50 of the lateral wings 29^a and thus leave a space slightly less than the diameter of the rod section 26 of the bolt and hence a little force is required to press such extension 55 into place upon the cylindrical rod member, 60

but when the rod member has been forced 65 in between the sides of the extension 32 such extension acts as a clip to hold the two parts together at that point. On the upper end of the member 28 and beyond the wings 29^a the metal of the structure is turned into 70 the form of a tube, indicated by 33, in which is located a stud 34 that is secured in place by a rivet 35 or otherwise—the upper end of the stud projecting from the tube 33 sufficiently to enter the socket covered by the 75 socket plate *a*, and thereby lock the upper end of the door in closed position. 36 indicates a plate secured against the face of the door *A* near the upper part of the door and opposite the plate member 28. It is 80 secured in place by means of screws passing through the turned ends of clips 37 and 38, respectively, which clips extend over the end portions 33 and 32, respectively, of the plate member 28 and while holding such 85 plate member in place permit it to have the limited vertical movement required to draw the stud 34 out of or project it into the socket in the upper frame of the doorway. These clips form stops against which 90 the ends of the wings 29^a abut and hence regulate the extent to which the plate member can be moved. As shown, the plate 36 has its central portion raised so that its wings 29^a bear lightly against such raised 95 portion.

To the lower end of the arm 21 is secured a stud 23^a corresponding to the stud 23 on the upper arm, and on such stud 23^a is mounted a depending bolt section 22^a corresponding to the bolt section 22. As the distance from the actuating shaft 15 to the lower edge of the door is less than the distance from such shaft to the upper edge of the door I have, in the construction shown, omitted a bolt section such as 24 and have connected the bolt section 22^a directly to a bolt section 26^a that corresponds to the bolt section 26, such connection of the two parts being by means of a nut 27^a. To this lower bolt section is attached an adjustable plate section indicated by 28^a and which is in all respects constructed and arranged as is the plate section 28, and hence needs no further detailed description. The parts that correspond to the parts already described are indicated in like manner but with the addition of the letter *a*.

Many door structures will be of such height that even in connection with the upper part of the door securing mechanism the section 24 of the bolt may be omitted as is the case with the lower part, and the several bolt sections may be of various lengths as required for different heights of doors. Regardless of the number of sections of which the locking bolt may be composed it is evident that by reason of the wide range of ad-

justability up and down of the two plate members 28-28^a that carry the projecting locking studs 34-34^a, respectively, the bolt as a whole can be properly applied and fitted 5 to doors varying to a considerable extent in height, and when a door having unusual height is to be fitted out with such mechanism that can be readily done without any change whatever in the mechanism other 10 than inserting an additional bolt section such for example as 24. While the adjustment of the plate sections up or down and locking them in different adjusted positions by passing the pin 31 through any two aligned 15 openings 30 will always bring the projecting stud 34 or 34^a, as the case may be, into approximately correct position for fully entering its socket, yet a finer adjustment to bring about the required exact degree of 20 projection of such stud may be had by turning one of the bolt sections with respect to one of the adjusting nuts that connect such sections together.

In addition to providing a construction 25 of locking bolt that will adapt it to be readily and properly applied to doors of varying heights it is very desirable also that means be provided for adapting to doors of different thicknesses the devices through 30 which such bolts are projected into and retracted from their sockets, for it is of course to be understood that such operating means must pass through a door so that operation of the bolts can be had by a person at either 35 side of the door. In connection with such bolt operating means it is necessary also in many circumstances to provide a lock upon the outer face of the door which will effectively prevent the bolts being retracted from 40 their sockets by unauthorized persons. Referring now to the bolt operating means and the locking means mentioned,—39 indicates a recess cut in the outer face of the door into which projects a lock casing 40 whose face 45 plate 41 will have its marginal portion preferably flush with the outer surface of the door as shown, the lock casing as a whole being secured in place by screws 42 as shown. Centrally through the front and 50 rear walls of the casing is a large circular opening 43 and opposite the said central openings in the front and back walls of the casing is rotatably mounted a disk 44 provided with an extension 45. Through this 55 rotatable disk 44 is a large rectangular shaped opening 46, into which opening from the outer face of the lock projects a shank 47, which, in the form of construction shown, (see Fig. 6), is formed of a single strip of 60 metal bent upon itself into the form of a yoke and having pivoted to it by a pin 48 passing through it near its closed ends a handle member 49 which is here shown as formed of a single piece of bent metal. The

two separated arms of the member 47 extend for a considerable distance beyond the rear face of the lock case 40 and lie snugly against the side walls of the large rectangular opening 46 in the disk 44. Fitted upon the projecting ends of the two arms of the member 47 is a comparatively long hollow sleeve 50 having a substantially rectangular appearance in cross-section. The arms of the member 47 lie against the sides of this angular sleeve 50 and may be secured thereto 75 by rivets or otherwise. The ends of the arms of the member 47 extend to substantially the farther end of the sleeve and thereby leave a central opening in such sleeve that is substantially square in cross-section and 80 that is of a size to snugly receive the end of the square rock-shaft 15 before referred to. By reason of such fitting of the shaft 15 in the sleeve it is evident that a turning of the sleeve caused by a rocking of the member 85 47 will correspondingly rock such shaft, and the rocking of such shaft will, of course, cause a projection or retraction of the sectional locking bolts as will be understood. Such movement can be had while the members of the locking mechanism contained in the casing 40 are in the position shown in full lines in Fig. 8, and the full lines therein 90 that show the rotatable disk show the position that such disk will be in when the sectional locking bolts have been projected to lock the door against movement. When in that position and it be desired to lock the parts so that the sectional bolts cannot be retracted, a sliding latch 51 is caused to be 95 moved by means of a key inserted through the lock so that a turned end or flange 52 of such latch will project over the lateral arm 45 of the disk and prevent any rotary movement of the disk and consequently preventing any turning of the member 47 or the shaft 15. The lock is provided with spring 100 pressed tumblers, one of which is shown and indicated by 53, which must be moved by a key as usual before the latch can be moved 110 into movement over the fixed contacts.

54 indicates a covering plate over the arms 20-21 and the devices immediately connected therewith. Such covering plate is preferably formed from a heavy sheet of 115 metal and provided with wide flanges so as to have the face of the plate stand out sufficiently to form between it and the plate 16 against the door a chamber in which the arms 20 and their immediate connections are 120 housed. The side flanges of the plate incline toward each other at the ends of the plate and at such ends the metal is bent into channel shape as at 55, which channel shaped portions lie opposite channeled or grooved 125 end portions 56 in the plate 16, such opposed channel portions thus forming guides in which the sections of the bolt that are

connected with the arms 20 and 21 respectively can be reciprocated. 57 indicates a ring rotatably mounted in an opening formed in the central portion of the plate 54, through which ring is an angular opening of a size and shape to receive the shaft 15, such ring thus forming a rotatable bearing for the shaft.

When a door is to be equipped with my improved devices a recess 39 in the front face thereof will first be made to receive the lock casing and the opening made leading through the door from the central portion of such recess, as shown in Fig. 5. The lock casing will then be attached in place and the two armed shank 47 then forced through the rectangular opening 46 in the disk 45 after which the angular sleeve 50 will be pushed upon and secured to such shank. Before the plate 16 is applied to the inner face of the door the shaft 15 will be inserted in the sleeve and between the arms 47 of the handle shank, and the extent to which it will be so inserted will depend upon the thickness of the door. I provide simple means for preventing the withdrawal of the shank, which, as shown, consists of a piece of wire 58 bent around the shaft and resting in a shallow groove 58 cut in the faces thereof. This piece of wire lies immediately behind the plate 16 and the central portion of this plate is slightly pressed out as shown and through an opening in which the shaft passes. Upon the plate 16 being then secured in place the wire 58 attached to the shaft 15 as explained will prevent withdrawal of the shaft. The rotatable disks 17 with the arms 20 and 21 attached thereto are then placed in position upon the shaft and the bolt sections 22 and 22^a pivotally connected to such arms, respectively, and thereafter the inclosing plate 54 with its bearing ring 57 is slipped over the shaft, the bearing ring itself being held in place by reason of its headed inner end bearing against the outermost disk 17. The plate is then to be secured by screws as shown in Fig. 3, which screws also pass through the plate 16 and secure it to the door. Upon the squared end portion of the shaft that projects beyond the plate 54 is mounted a handle 60 which is held in place by a nut 61 screwed upon the threaded end of the shaft. With the parts so far referred to assembled as stated a cylindrical bolt section such as 24 may be coupled to the section 22 or 22^a, but if not so required then the adjustable plate section 28 may be properly adjusted upon a bolt section that is connected by a nut to the section that is pivotally connected to one of the curved arms 20 or 21. These plate sections will, by the means described, be adjusted to approximately the exact position to have their locking studs enter their respective sockets, and for a finer adjustment, in

order to have the throw of the bolt exactly right, resort will be had to the nuts that connect the cylindrical bolt sections together.

What I claim as my invention and desire to secure by Letters Patent, is—

1. The combination with a door, of a horizontal angular rock-shaft connected therewith and projecting therefrom, a pair of oppositely-extending locking bolts, means on the projecting portion of said rock-shaft for projecting and retracting said bolts when the shaft is rocked, a cover plate secured to the door and forming a housing for said bolt-operating means, said housing having an opening through its wall for the passage of the shaft, and a bearing for the shaft rotatably mounted in such opening.

2. The combination with a door, of a horizontal angular rock-shaft connected therewith and projecting therefrom, a pair of oppositely-extending locking bolts, means on the projecting portion of said rock-shaft for projecting and retracting said bolts when the shaft is rocked, a cover plate secured to the door and forming a housing for said bolt-operating means, said housing having an opening through its wall for the passage of the shaft, and a bearing for the shaft rotatably mounted in such opening, the end portions of said housing being contracted to form guides for said bolts.

3. The combination with a door, of a rock-shaft connected therewith and projecting therefrom, a sectional bolt extending along one face of the door, means connected with said shaft and bolt for causing a longitudinal movement of the bolt when the shaft is turned, said bolt comprising a rod member and a member formed of a plate having an outwardly-bowed central portion for receiving the rod member, and means for connecting said two members together in different relative positions.

4. The combination with a door, of a rock-shaft connected therewith and projecting therefrom, a sectional bolt extending along one face of the door, means connected with said shaft and bolt for causing a longitudinal movement of the bolt when the shaft is turned, said bolt comprising a rod member and a member formed of a plate having an outwardly-bowed central portion for receiving the rod member and having lateral wings forming bearing surfaces, and means for connecting said two members together in different relative positions.

5. The combination with a door, of a rock-shaft connected therewith and projecting therefrom, a sectional bolt extending along one face of the door, means connected with said shaft and bolt for causing a longitudinal movement of the bolt when the shaft is turned, said bolt comprising a rod member and a member formed of a plate having an outwardly-bowed central portion

for receiving the rod member, a socket-engaging stud secured at the outer end of said plate member, and means for connecting said two members together in different relative 5 positions.

6. The combination with a door, of a rock-shaft connected therewith and projecting therefrom, a sectional bolt extending along one face of the door, means connected 10 with said shaft and bolt for causing a longitudinal movement of the bolt when the shaft is turned, said bolt comprising a rod member and a member formed of a plate having an outwardly-bowed central portion 15 for receiving the rod member, lateral wings forming bearing surfaces, a cylindrical extension at the outer end, a socket-engaging stud secured in such extension, and means for connecting said two members together 20 in different relative positions.

7. The combination with a door, of a rock-shaft connected therewith and projecting therefrom, a sectional bolt extending along one face of the door, means connected 25 with said shaft and bolt for causing a longitudinal movement of the bolt when the shaft is turned, said bolt comprising a rod member and a member formed of a plate having an outwardly-bowed central portion for receiving the rod member, lateral wings forming bearing surfaces, an extension at the outer end, a socket-engaging stud secured to such extension, a curved extension at the inner end forming a spring clip adapted to 30 be sprung over and engage the rod member, and means for connecting said two members together in different relative positions.

8. The combination with a door, of a rock-shaft projecting beyond one face of the door, 40 a pair of oppositely-projecting locking bolts, means on said projecting portion of the rock-shaft for projecting and retracting said bolts when the shaft is rocked, a rotatable shank extending into the door from the opposite 45 side and having a longitudinally-movable but non-rotatable engagement with said shaft, and means for holding said shank and shaft from endwise movement.

9. The combination with a door, of a rock-shaft projecting beyond one face of the door, 50 a pair of oppositely-projecting locking bolts, means on said projecting portion of the rock-

shaft for projecting and retracting said bolts when the shaft is rocked, a rotatable shank extending into the door from the opposite 55 side, said shank comprising two arms spaced apart to receive between them the said shaft, and means for holding said shank and shaft from endwise movement.

10. The combination with a door, of a rock-shaft projecting beyond one face of the door, 60 a pair of oppositely-projecting locking bolts, means on said projecting portion of the rock-shaft for projecting and retracting said bolts when the shaft is rocked, a rotatable shank extending into the door from the opposite 65 side, a sleeve connected with said shank and receiving the inner portion of said shaft, said shaft and sleeve having a sliding but non-rotatable engagement with 70 each other, and means for preventing withdrawal of the shaft from the sleeve.

11. The combination with a door, of an angular rock-shaft projecting beyond one face of the door, a pair of oppositely-projecting locking bolts, means on said projecting portion of the rock-shaft for projecting and retracting said bolts when the shaft is rocked, a rotatable shank extending 75 into the door from the opposite side, said shank comprising two arms spaced apart, a sleeve into which said arms extend and into which the shaft also extends, said shaft lying between said arms, and means for preventing withdrawal of the shaft from 80 the sleeve.

12. The combination with a door, of a casing containing locking mechanism secured to one face of the door and comprising a rotatable member having an opening 90 therethrough, a shank extending through said casing and said rotatable member and engaging the latter to cause a turning thereof when the shank is turned, key-operated means in said casing for locking said 95 rotatable member against movement, a rock-shaft non-rotatably but slidably connected with the inner portion of said shank, means for preventing withdrawal of the shaft from its connection with the shank, a pair of oppositely projecting locking bolts, and means carried by the shaft and connected with said bolts for projecting and retracting the bolts. 100

ELLIS J. G. PHILLIPS.
